[57] **CLAIM**

The ornamental design for the ceiling fixture housing, as shown and described.

DESCRIPTION

FIG. 1 is a bottom view of the ceiling fixture housing embodying my new design; the broken lines showing a fan, blades and overall ceiling fixture are for illustrative purposes only and form no part of the claimed design;

FIG. 2 is a front perspective view of ceiling fixture housing; the broken lines showing a fan, blades and overall ceiling fixture are for illustrative purposes only and form no part of the claimed design; and,

FIG. 3 is a front view of the ceiling fixture housing; the broken lines showing a fan, blades and overall ceiling fixture are for illustrative purposes only and form no part of the claimed design.

The top of the housing is identical to the bottom as shown in FIG. 1, and the sides and rear of the housing are identical to the front as shown in FIG. 3.
